D 16195

UNITED STATES PATENT OFFICE.

JAMES H. ALEXANDER, OF PHILADELPHIA, PENNSYLVANIA, ASSIGNOR TO
THOMAS DEVLIN & CO., OF SAME PLACE.

DESIGN FOR A PLATE FOR CARRIAGE-STEPS.

SPECIFICATION forming part of Design No. 16,195, dated August 11, 1885.

Application filed June 8, 1885. Term of patent 14 years.

To all whom it may concern:

Be it known that I, JAMES H. ALEXANDER, a citizen of the United States, residing at Philadelphia, in the county of Philadelphia and State of Pennsylvania, have invented a certain new and useful Design for Step-Plates for Carriages, &c.; and I do hereby declare the following to be a full, clear, and exact description of the invention, reference being had to the accompanying drawing, which forms part of this specification, in which the figure is a plan of the same.

This invention has relation to designs for the step-plates of carriages; and said design consists of a step-plate having intersecting ridges forming diamond-shaped recesses or cells, the bottoms of which have circular openings.

A represents the step-plate, which is rectangular in outline, with an ogee edge or rim, B. C C' are oblique ridges extending from side to side and intersecting at such angles as to form triangular cells or recesses D around the edge and diamond-shaped recesses or cells

E over the rest of the plate or the major portion thereof. The bottoms of the cells E have circular holes e.

The triangular cells D and the diamond-shaped cells E may form the entire configuration of all the plate inside the edges; or a part of the ribs C C' may be omitted at the middle of the plate, so as to leave a large diamond-shaped cell, F, which incloses an initial or letter.

What I claim as my invention is—
The design for a step-plate, consisting of a plate having intersecting ridges, which form diamond-shaped recesses or cells, the bottoms of which have circular openings, substantially as shown and described.

In testimony that I claim the foregoing I have hereunto set my hand this 14th day of May, 1885.

JAMES H. ALEXANDER.

Witnesses:

ISAIAH MATLACK,
WILL H. POWELL.

DEPARTMENT OF THE INTERIOR,

UNITED STATES PATENT OFFICE,

WASHINGTON, D. C., *August 18, 1885.*

Whereas Messrs. Connolly & Bros., attorneys for the parties in interest, have, in writing, refused to receive Letters Patent No. 16,195, granted August 11, 1885, upon the application of James H. Alexander, of Philadelphia, Pennsylvania, for a "Design for Plate for Carriage-Steps," for the reason that the drawing attached thereto is not that pertaining to nor allowed in the case, and—

Whereas an examination shows that said Letters Patent were not issued in accordance with the official record of the case,

*It is hereby ordered that the seal of said Letters Patent be broken, the grant returned to the file marked *canceled*, and that Letters Patent, in proper form, be issued pursuant to the record of the case in the Patent Office.*

M. V. MONTGOMERY,
Commissioner of Patents.

Approved:

H. L. MULDROW,
First Assistant Secretary of the Interior.
